UNITED STATES PATENT OFFICE.

WILLIAM SPARKS, OF JACKSON, MICHIGAN, ASSIGNOR TO THE SPARKS-WITHINGTON COMPANY, OF JACKSON, MICHIGAN, A CORPORATION OF OHIO.

BRACKET.

Application filed December 23, 1924. Serial No. 787,510.

To all whom it may concern:

Be it known that I, WILLIAM SPARKS, a citizen of the United States of America, of Jackson, in the county of Jackson, in the 5 State of Michigan, have invented new and useful Improvements in Brackets, of which the following, taken in connection with the accompanying drawings, is a full, clear, and exact description.

10 This invention relates to certain improvements in horn brackets or supporting arms designed particularly for supporting a motor-driven horn upon the engine of an automobile beneath the hood in a manner 15 to permit limited vibratory movement of the horn.

Experience has demonstrated that practically every make of vehicle requires a bracket of special construction for supporting the 20 horn used as regular equipment thereon, and the same is also true of horns sold at retail for installation upon individual cars. It is, therefore, a great economy in time and 25 money to provide a bracket that is adapted for supporting a horn upon practically any type or make of car. Further, certain types of horns require a resilient support, which permits limited vibratory movement of the 30 horn if the desired character of sound is to be emitted from the horn.

The features of improvement of this bracket, therefore, include the fact that it not only permits limited vibratory movement of the horn, but may be used and fits 35 equally as well either side up, lessens breakage by placing the strain of supporting the horn substantially equally upon both cylinder head bolts, and is capable of installation upon almost any design or size of internal combustion engine.

Other objects and advantages relate to the details of the structure, all as will more fully appear from the following description, taken in connection with the accompanying 45 drawings, in which:

Figure 1 is a perspective view of the bracket.

Figure 2 is a section on line 2—2, Figure 1.

50 Figure 3 is a section on line 3—3, Figure 1.

The bracket as illustrated, comprises two relatively adjustable parts —1— and —2—. The part —2— constitutes the more immediate support for the horn, and comprises a

comparatively short strip of sheet metal formed in a channel with the flanges —3— and —4— upon opposite sides thereof, which flanges are integral with the strip —2—, and are bent at substantially right angles 60 to the strip, and are preferably of a length substantially equal to the thickness of the strip —1— and are spaced apart a distance practically just sufficient to receive the strip —1— so as to maintain a predetermined 65 alignment of the two parts —1— and —2—.

The part —2— is further provided with a bolt-receiving flange —5— preferably of considerably greater length than the flange —3—, and formed upon the same side of the strip —2— as the flange —3— and spaced 70 from the flange —4— a distance somewhat greater than the width of the strip —1—, whereby the bolt-receiving flange —5— is relieved of any of the strain of maintaining 75 the parts —1— and —2— in alignment.

The part —2— may, as shown, be provided with an elongated slot —9— and the strip —1— with a series of bolt-receiving 80 openings —10—, any one of which openings can be brought into over-lying relation with a portion of the slot —9— so that a bolt —11— may be passed through the slot and any one of said openings —10— and the 85 parts —1— and —2— may be clamped together by means of a nut —12— mounted on the bolt —11—. Preferably, a split-washer —23— is interposed between the nut —12— and the strip —2— and the openings —10— and the strip —1— are pref- 90 erably of angular form, as for instance, square, so as to receive a square portion of the bolt and the strip —1—.

For the purpose of resiliently supporting a horn from the relatively adjustable parts —1— and —2—, as heretofore described, the part —2— at its inner end is formed with an outwardly projecting flange —13— pref- 95 erably projecting at substantially right angles to the strips —1— and —2—. A pair of spring plates —14— and —15— are disposed upon one side of the flange —13— and these plates are formed at their outer end with arcuate shaped edges —16— and —17— having at their opposite ends bolt receiving 100 openings —28— and —19—. The portion of these plates overlying the flange —13— are formed with openings for receiving bolts or rivets —20— for securing the spring- 105 plates —14— and —15— to the flange 110

—13—. A pair of similarly shaped and formed spring or resilient plates —21— and —22— are disposed in similar position upon the opposite side of the flange —13— and the openings through the respective resilient plates —14—, —15—, —21— and —22— are all in alignment, so that the rivets —20— pass through the openings in all of the resilient plates and through the flange —13—

10 and secure these parts permanently together.

At the outer ends adjacent the arcuate edges a spacing strip —18— is provided positioned between the resilient plates —15— and —21—, and its outer edge is 15 arcuate shape to conform with the curved shape of the outer edge of the plates —14—, —15—, —21— and —22— and at its opposite ends it is provided with bolt-receiving openings aligned with the openings —28— 20 and —19— in the plates —14— and —15— and the similarly formed and positioned openings in the plates —21— and —22—, and through these openings in the resilient plates and the spacing member 18 bolts 25 are adapted to be passed for securing these parts to a horn structure.

It will be obvious that the resilient plates —14— and —15—, and —21— and —22— constitute the sole connection between the 30 horn structure and the adjustable sections —1— and —2— of the bracket whereby limited vibratory movement of the horn structure is permitted for the purpose of obtaining the desired character of sound from the 35 horn. Further, the flange —13— as illustrated, which carries the resilient horn-at-

taching flange, is positioned in the completed structure at an intermediate point along the strip —1— and such strip extends forwardly from the flange —13— some distance and is provided at or near its front end with a bolt-receiving flange —8— similar to the flange —5— and in alignment therewith.

Altho I have shown and described a specific construction as illustrative of a perhaps preferred embodiment of my invention, I do not desire to limit myself to the details of form, construction or arrangement, as various changes may be made in each all 50 within the scope of the appended claim.

I claim:

A bracket comprising two parts adjustable longitudinally with respect to each other, means for securing said parts in various adjusted positions, one of said parts formed with a laterally-extending flange, a pair of spring-plates disposed upon opposite sides of said flange and secured to the flange and having their outer edges of arcuate 60 shape, and formed at opposite ends with aligned bolt-receiving openings for securement to a horn, and a spacing member between the outer portion of said spring plates and having openings aligned with the bolt-receiving openings through the plates.

In witness whereof I have hereunto set my hand this 29th day of November, 1924.

WILLIAM SPARKS.
